(57) **CLAIM**

The ornamental design for a pasta, as shown and described.

DESCRIPTION

FIG. 1 is a front elevation view of a pasta showing my new design, the rear elevation view being identical thereto;

FIG. 2 is a top plan view thereof;

FIG. 3 is a bottom plan view thereof;

FIG. 4 is a right side elevation view thereof, the left side elevation view being identical thereto; and,

FIG. 5 is a cross-section view thereof taken along line 5-5 in FIG. 2.
